UNITED STATES PATENT OFFICE

GUSTAV A. CARLSON, OF CHICAGO, ILLINOIS, ASSIGNOR TO THE BOYE NEEDLE COMPANY,
OF CHICAGO, ILLINOIS, A CORPORATION OF ILLINOIS

LOOP-FORMING NEEDLE

Application filed October 3, 1930. Serial No. 486,252.

This invention relates particularly to a needle adapted to the purpose of making rugs, or other articles, where it is desirable to pass yarn through a foundation fabric, such as burlap, and form loops at one side of the fabric, thus providing a "nap". The loops may afterwards be cut to permit the yarn to spread and form a fuzzy nap.

The present invention is in the nature of an improvement upon the device disclosed in my pending application Serial No. 486,251, filed of even date herewith; and the primary object is to provide a simple and secure form of connection between the needle, proper, of a device of this character and its handle.

The invention is illustrated in a preferred embodiment in the accompanying drawing, in which—

Fig. 1 is a side view of a needle device embodying the invention; Fig. 2, a plan view of the needle and the fitting or socket-member with which it is equipped; Fig. 3, a broken sectional view taken as indicated at line 3 of Fig. 2, showing in detail the connection between the needle and handle; and Fig. 4, a transverse section taken as indicated at line 4 of Fig. 3.

In the illustration given, A designates a handle; and B, a semi-tubular needle equipped with a fitting B' which serves as a connector between the needle and the handle.

The needle preferably is of the construction described in the above-mentioned application. As shown, it is formed from a sheet-metal member 1 which is bent into tubular form, but which has a portion cut away, as indicated at 2.

The needle has a pointed tip 3 and a tubular shank-portion 4. The back wall of the needle is provided with eyes 5 and 6 through which the yarn may extend. As thus described, the needle has a longitudinal channel 7 through which the yarn may extend in its passage from one eye to the other. Also, as shown, the back wall of the needle is struck inwardly at points 5^a and 6^a to provide thread-grooves adjacent the eyes.

The fitting B' preferably is of a form which permits it to be made on a screw ma-

chine. As shown, it comprises a knurled portion 8 and a threaded shank 8^a. Part 8 is provided with a bore or socket 8^b which receives the shank-portion 4 of the needle by a tight, slip-joint connection.

The handle A is shown equipped with a ferrule, or cap, 9 which has a sleeve-portion fitting over the reduced end of the handle and which has an end-portion 9^a having an inwardly struck boss, or small tubular part 9^b, which is tapped to afford a socket for the threaded shank 8^a of the fitting B'. The part 9^b fits into a bore 10 with which the handle is provided. If desired, the metal socket 9^b may be formed independently of the ferrule.

This is the preferred construction, but, if desired, the thread-connection between the shank 8^a and the socket 9^b may be omitted.

The construction described affords a firm, secure connection between the needle and handle. Moreover, the needle is readily removable from the handle, thus enabling another needle to be substituted, at will.

What I regard as new and desire to secure by Letters Patent, is:

A device of the character described comprising a handle having one end provided with a bore and equipped with a ferrule embracing the end of the handle and having a threaded metallic socket integral with said ferrule and received by said bore; a fitting comprising a part provided with a bore and having a reduced threaded shank received by said socket; and a needle comprising a sheet-metal member having a tubular shank-portion fitted within said second-mentioned bore.

GUSTAV A. CARLSON.
